UNITED STATES PATENT OFFICE.

ARCHIE NOEL JETTE, OF ANACONDA, MONTANA.

REVERBERATORY SMELTING FURNACE.

Application filed August 10, 1920. Serial No. 402,556.

To all whom it may concern:

Be it known that I, ARCHIE NOEL JETTE, a citizen of the United States, residing at Anaconda, in the county of Deerlodge and 5 State of Montana, have invented certain new and useful Improvements in Reverberatory Smelting Furnaces, of which the following is a specification.

This invention relates to metallurgical 10 smelting furnaces of the reverberatory type, and in particular to reverberatory copper smelting furnaces.

The main object of this invention is to provide a reverberatory furnace whereby 15 the metallurgical and mechanical operations are made more convenient and, in general, the metallurgical as well as the mechanical efficiency of the furnace improved.

The improvements relate to various features of such furnaces including (1) an improved arrangement and construction of the flue connections by which the hot waste gases, dust and fume from the furnace proper are carried off; (2) an improved ar- 20 rangement of the furnace bottom; (3) an improved water-cooled tap-hole and skimming plate; (4) an improved slag launder; (5) an improved arrangement of the longitudinal bracing and tying provisions of a 25 reverberatory furnace, which includes a special construction of side skew-back plates which function also as supports for the main arch of the furnace roof.

The invention will best be understood in 30 connection with the accompanying drawings in which—

Fig. 1 is a side elevation, parts being broken away.

Fig. 2 is a longitudinal section of the 40 furnace.

Fig. 3 is a horizontal section of one end of the furnace.

Fig. 4 is an end elevation of the tapping end of the furnace.

Fig. 5 is a view in perspective of the interior of the furnace at the flue connection.

Fig. 6 is an elevation of a portion of the end of the furnace showing the water-cooled slag and tap holes.

Fig. 7 is a section on plane A—A of Fig. 6.

Fig. 8 is a section on plane B—B of Fig. 6.

Figs. 9 and 10. are a plan and perspective side elevation of the slag launder.

The various features of improvement will 55 be discussed in detail.

1. *The flue connection.*

This improvement refers chiefly to a flue for carrying hot waste gases, dust and fume 60 from the furnace proper, designed and constructed with the idea of providing what might be termed a secondary chamber or flue, of such ample dimensions, arrangement and construction of parts as to immediately 65 relieve the furnace of the hot waste gases carrying the fusible ash and dust.

The connection between the furnace and this flue is the terminal of the reverberatory arch, after which point smelting proper no 70 longer takes place.

In metallurgical furnaces of the reverberatory type the smelting is accomplished by virtue of the heat from the hot gases or products of combustion from the burning 75 of the fuel under the reverberatory main arch, the heat being concentrated by reflection from this arch onto the charge.

It has heretofore been the practice, in reverberatory smelting, to retain the hot gases 80 of combustion in the smelting chamber as long as possible, thus deriving the maximum benefit from the heat of the gases for smelting purposes. The point of exit from the furnace into the flue being the terminal of 85 the reverberatory arch, the hot gases after leaving the furnace proper, enter the enlarged flue connection and expand by virtue of this enlargement of chamber, decreasing, therefore, the intensity of heat and de- 90 creasing the tendency of the fusible ash and dust carried and precipitated therein to fuse or smelt. A sintering of these precipitated solids takes place permitting their removal through clean-up doors provided 95 for that purpose.

But, in the design and construction of this part of reverberatory furnaces in the past, the slag dam, on which these sintered solids precipitate, was constructed of such height 100 as to bring its level above the level of the reverberatory arch, thus producing a contracted area in the passageway through which the hot gases carrying the fusible ash and dust were compelled to pass into the flue proper. This contraction caused a concentration of heat at this point and a resultant fusing or smelting of the solid

material precipitated on or carried over the floor of the slag dam and flue entrance. With such a construction the floor of the slag dam was of such height as to make the removal of this fused or partly fused material, from the slag dam and culvert proper, extremely difficult, with the result that material accumulated in the passageway at a rapid rate and resulted in the closing up of the opening. As this process of closing up continued, the area became less, the intensity of the heat therein became greater, increasing, therefore, the detrimental effect of fusing and smelting of the ash and dust carried from the furnace by the hot gases and in general resulting in a choking off of the furnace.

The cross-sectional area of this flue connection was, in the past, purposely made small in an attempt to retain the hot gases in the furnace proper for smelting purposes as long as possible. In many cases a damper in this flue of small cross-sectional area was omitted, because of two reasons:— the first being that the concentration of heat in this small passageway was so intense as to make impossible the use of a damper; secondly, because it was believed that with the design of a flue of small cross-sectional area, the flow of hot gases would be thereby choked and restrained in the furnace, for smelting purposes, and a damper being therefore unnecessary.

My improvement to this part of reverberatory furnaces provides for a radical change in this policy. Instead of attempting to accomplish the desired smelting conditions by a contraction of flue area and the omission of a damper, just the opposite has been done, namely, the flue area has been enlarged and a damper installed.

The improved construction of the furnace will be understood from Figs. 1 to 5, in which A is the bed of the furnace, and B the arched roof. The firing end of the furnace is shown at the right of Figs. 1 and 2, gas, oil, or coal being used. The flue connection is shown at the left of Figs. 1 and 2.

Referring to Fig. 5, it will be noted that, at the end of the arched roof, there is provided a cross flue or culvert of large cross-sectional area. At each side of this cross-flue is provided a slag-dam C, of solid masonry construction, whose floor is considerably below the crown of the roof-arch B, and just above the normal slag-level maintained in the furnace. This lowering of the level of the floor of the slag-dam enables the workmen to remove accumulations thereon, while standing on the working floor of the furnace. Openings D, D, D, closed by suitable doors are provided to give the workmen access to the floor of the slag-dam. Movable dampers E, E, are provided at the sides of the cross-flue or culvert.

As shown in Figs. 3 and 5, the reverberatory arch is arched in a vertical plane and has its terminal wall arched also in a horizontal plane, as indicated by the letter S. The vertical plane arch supports the weight of the roof or arch proper. The horizontal plane arch resists longitudinal pressures.

By virtue of this flue of large cross-sectional area, the gases expand as they leave the furnace proper, the heat concentration diminishes, the regulation of gas flow is accomplished by manipulation of the damper, and the retention of the hot gases in the furnace is accomplished to the desired extent. The closing up of the passageway by accumulation of material fusing to the side walls, on which sticky surface dust readily adheres, is obviated, since any such accumulations are readily removed through openings D, D, D; and the freer flow of gases causes the solid material carried by the gases to precipitate at points where their removal is easy, and in a fluffy condition which makes them easy to handle. It thus becomes possible to maintain a full-size flue opening throughout the campaign of the furnace, while obtaining by use of the dampers a close regulation of operating conditions. The improvement is of special importance in connection with reverberatory smelting where lead, zinc, or arsenic fumes are to be recovered by precipitation in Cottrell treaters, bag-houses and the like.

2. The furnace bottom.

The bottom A of the furnace, which is preferably made of quartz sand is, as shown in Fig. 2, inclined downwardly from the burner end toward the tapping end. There is thus provided a flow of the molten charge to the metal bay, the increased thickness at the burner end filling the space which would otherwise be needlessly occupied by metal or furnace charge, thus tying up a large capital in valuable material as a permanent inventory charge. As these furnaces are more than 100 feet long, this item is of importance. The slope, depth and character of this bottom is a matter of choice depending on the conditions and requirements in each case.

3. The water-cooled tap hole and skimming plate.

As shown in Figs. 6, 7 and 8, a cast-iron plate G is set in the masonry at the end of the furnace, a system of water-cooling pipes, H, being embedded in the plate. Above the plate G is located the skimming block I, provided with a gate J. Through the opening K, fluid slag is withdrawn. Tapping holes L, L, are also provided in the plate, preferably two at different levels, either one of which may be used in case the other becomes clogged or frozen up.

Each tap hole is provided with an apertured tap-hole block M held in place by wedges N, N', passing through apertured ears or lugs on the plate G. Should the aperture in the tap-hole block become burnt out or enlarged to too great a degree, the wedges can be knocked out and a new block installed in a few minutes.

10 4. *Slag launder.*

To facilitate removal of the slag which flows from the furnace over the skimming block I, I provide the outer end of this block with a semi-cylindrical groove portion O, into which fits a correspondingly shaped tongue P on the end of a section of the slag launder, each section Q, Q, Q, having at its ends correspondingly shaped engaging portions. These sections are preferably curved, so that the flowing slag may be delivered to one side of the furnace.

The advantages of such an arrangement are many. It not only provides for a quick and easy removal of the skimming block or any section of the slag launder which may become broken or worn out, but it also provides for a good, strong, simple installation installed above the floor level so that there exists an air space completely around it eliminating the necessity of excavation when repairs are necessary and more important, allowing a radiation of heat, thus insuring a longer life. The cast iron of the launder is protected from the hot molten slag by any form of lining such as brick, fire-clay or any material resisting the action of molten slag.

R, R, are squared off portions on each section of the launder to rest on suitable supports.

40 The improvements to the furnace bottom with its sloping feature and the installation of the water cooled tap hole plate and skimming block as heretofore described and illustrated make it possible to operate with a continuous flow of slag from the furnace. This feature of furnace operation is all important and is only made possible by the design and construction of a furnace with the improvements as stated above. The water cooled tap hole plate makes it possible to maintain a larger bay of metal. Continuous skimming is an advantage in reverberatory furnace operations and is believed to be new.

55 Further improvements, as parts of my invention relate to the mechanical construction of the furnace roof and to the means for supporting it.

60 5. *The side skew-back plates.*

These plates are made of beams or girders secured together, and extend along each side of the furnace from end to end; and function in a two-fold capacity, namely as supports for the main arch of the furnace roof,

and also as ties between the two ends of the furnace. These plates may be of any width desired, even to the extent of covering the whole furnace side. As shown in Fig. 1, the main plate 10, extends the length of the furnace, and is provided at each end with braces 11, 11. The ends of the main plate and the braces, are secured directly to beam structures 12, 12, bearing against the ends of the furnace. By the use of these lateral skew-back plates, the tie rods extending over the furnace top are eliminated; and head room is provided for repairs to the furnace roof. The former construction necessitated a large number of iron rods of large diameter, which were liable to occasional breaking. The skew-back plates bear against the sides of the furnace and are held against transverse movement by vertical beams 14, 14, and buck-stays.

70 As shown in Fig. 2, there are provided at each side of the furnace roof, a series of openings 20, 20, through which the charge is introduced into the furnace.

75 6. *The furnace roof.*

At frequent intervals, along the furnace roof, are arched ribs 21 conforming with the main reverberatory arch and built in and connected therewith. These ribs consist of the same material, as in the reverberatory arched roof and function as an additional support to the reverberatory roof, providing a support for sections of the roof that have burned thin and would otherwise drop.

80 The roof is made in sections between which are left openings acting as expansion joints.

The slag launder, tap hole and skimming plate, etc., form the subject matter of application Ser. No. 434759 filed Jan. 3, 1921, and 85 the side skew-back plates form the subject matter of application Ser. No. 434760 filed Jan. 3, 1921.

I claim:

1. A reverberatory furnace comprising a 90 furnace chamber and means for heating the same, a secondary chamber at the exit forming a metal bay, said secondary chamber being of sufficient size to permit the gases coming from the furnace to expand, and an 95 exit flue from the secondary chamber having a damper therein.

2. Furnace according to claim 1 in which the secondary chamber extends a substantial distance above the arch of the furnace 100 roof.

3. Furnace according to claim 1 in which the flue is of such cross-sectional dimensions as to constitute another expansion chamber, in addition to said secondary chamber, for 105 permitting the gases to expand and thereby materially diminishing the heat concentration at the end of the furnace.

4. A reverberatory furnace comprising a 110 furnace chamber and means for heating the

- same, a secondary chamber at the exit forming a metal bay, said secondary chamber extending a substantial distance above the arch of the furnace roof and having a relatively 40
 5 large cross-sectional area sufficient to permit the gases coming from the furnace chamber to expand and a flue having a damper, the flue being such cross-sectional dimensions as to constitute another expansion chamber, in
 10 addition to the said secondary chamber, for permitting the gases to expand and thereby materially diminishing the heat concentration at the end of the furnace.
5. A reverberatory furnace as claimed in
 15 claim 1 in which the secondary chamber has located therein a slag-dam whose upper level is below that of the crown of the arch of the furnace roof.
6. A reverberatory furnace as claimed in
 20 claim 2, in which doors are provided at the upper level of the slag-dam.
7. A reverberatory furnace comprising a furnace chamber and means for heating the same, a secondary chamber at the exit forming a metal bay, a flue from the secondary chamber defining a slag dam whose upper level is below the crown of the arch of the furnace roof, and doors adjacent the upper 25
 30 level of the slag dam, the secondary chamber having a relatively large cross-sectional area sufficient to permit the furnace gases to expand and the flue having such a large cross-sectional area as to additionally cause a material expansion of the furnace gases and a substantial decrease of the heat concentration at the end of the furnace.
8. Furnace according to claim 7 in which the secondary chamber extends a substantial distance above the arch of the furnace roof
- and the flue extends substantially to the roof 40
 of the secondary chamber.
9. A reverberatory furnace comprising a furnace chamber and means for heating the same, a secondary chamber at the exit forming a metal bay and flues extending from 45
 opposite sides of the secondary chamber defining slag dams whose upper level is below the crown of the arch of the furnace roof, the secondary chamber having a relatively large cross-sectional area sufficient to permit the 50
 furnace gases to expand and the flues having a relatively large cross-sectional area sufficient to additionally cause a material expansion of the furnace gases and a material decrease of the heat concentration at the end 55
 of the furnace.
10. Furnace according to claim 9 in which the secondary chamber extends a substantial distance above the arch of the furnace roof.
11. Furnace according to claim 10 in 60
 which the flues extend substantially to the roof of the secondary chamber.
12. Furnace according to claim 9 including a skimming outlet for slag and a tap hole for matte in the furnace end between 65
 the slag dams.
13. Furnace according to claim 2 in which the end of the arched roof of the furnace is arched horizontally as well as vertically.
14. A long reverberatory furnace of the 70
 kind described, having a bottom gradually sloping from the firing end to the discharge end, means for maintaining a bay of metal at the discharge end and means for permitting continuous skimming of the slag.
- In testimony whereof, I affix my signature.

ARCHIE NOEL JETTE.
